Primary Examiner—Catherine Tuttle

(74) Attorney, Agent, or Firm—Davidson Berquist Jackson & Gowdey LLP

(57) CLAIM

The ornamental design for an item holder, as shown and described.

DESCRIPTION

FIG. 1 is a frontal perspective of an item holder showing our new design;

FIG. 2 is a frontal view thereof;

FIG. 3 is a rear view thereof;

FIG. 4 is a left side view thereof;

FIG. 5 is a right side view thereof;

FIG. 6 is a top plan view thereof; and,

FIG. 7 is a bottom plan view thereof.

It should be understood that the broken line showing of portions of the item holder and held items in the figures is for illustrative purposes only and forms no part of the claimed design.

See application file for complete search history.
